CLAIM

The ornamental design for a telephone keypad for a combined radio, and clock telephone set, as shown above.

DESCRIPTION

FIG. 1 is a front and side perspective view from above of a telephone keypad for a combined radio, clock and telephone set showing my new design;

FIG. 2 is a top plan view thereof;

FIG. 3 is a left side elevational view thereof; and

FIG. 4 is a top plan view of a second embodiment of the design shown in FIG. 1.

The broken lines shown in FIG. 1 of the drawings are for illustrative environmental associational purposes only, and are not a part of the claimed design.

FIG. 2.

FIG. 3.

FIG. 4.
